UNITED STATES PATENT OFFICE

98,934

DESIGN FOR A BRACELET

Herman Luis Ernesto Gunther, Buenos Aires,
Argentine Republic

Application December 30, 1935, Serial No. 60,347
In Argentine Republic September 21, 1935

Term of patent 3½ years

To all whom it may concern:

Be it known that I, Herman Luis Ernesto Gunther, a citizen of the Republic of Uruguay, residing at Buenos Aires, Argentine Republic, have invented a new, original, and ornamental Design for Bracelets, of which the following is a specification, reference being had to the accompanying drawing, forming a part thereof.

Fig. 1 is a perspective view of a bracelet showing my new design,

Fig. 2 is a plan view of the same, and
Fig. 3 is an end elevation thereof.

I claim:

The ornamental design for a bracelet, substantially as shown.

In testimony whereof I affix my signature.

HERMAN LUÍS ERNESTO GUNTHER.
